US00D971426S

(12) **United States Design Patent** (10) Patent No.: **US D971,426 S**
Lieberman-Lu et al. (45) Date of Patent: **** Nov. 29, 2022**

(54) **HAND HELD VIBRATING ELECTROMECHANICAL STIMULATION DEVICE**

(71) Applicant: **Dame Products Inc.**, Brooklyn, NY (US)

(72) Inventors: **Janet Lieberman-Lu**, Brooklyn, NY (US); **Amanda Couto**, Pembroke Pines, FL (US); **David Block**, Brooklyn, NY (US)

(73) Assignee: **DAME PRODUCTS, INC.**, Brooklyn, NY (US)

(**) Term: **15 Years**

(21) Appl. No.: **29/721,192**

(22) Filed: **Jan. 17, 2020**

(51) LOC (13) Cl. **28-03**

(52) U.S. Cl.

USPC **D24/215**

(58) **Field of Classification Search**

(57) **CLAIM**

The ornamental design for a hand held vibrating electromechanical stimulation device, as shown and described.

DESCRIPTION

FIG. 1 is a bottom elevational view of a hand held electro-mechanical stimulation device showing our new design; FIG. 2 is a top elevational view thereof; FIG. 3 is a front elevational view thereof; FIG. 4 is a back elevational view thereof; FIG. 5 is a left elevational view thereof; FIG. 6 is a right elevational view thereof; FIG. 7 is a left, top and front perspective view thereof; FIG. 8 is a right, top and back perspective view thereof; and, FIG. 9 is a bottom, front and right perspective view thereof. The broken lines depict portions of the article that form no part of the claimed design.

1 Claim, 8 Drawing Sheets
